UNITED STATES PATENT OFFICE

2,095,687

HEEL-ATTACHING MACHINE

John W. Ashley, Beverly, Mass., assignor to
 United Shoe Machinery Corporation, Paterson, N. J., a corporation of New Jersey

Application February 27, 1936, Serial No. 66,074

24 Claims.

(Cl. 1—32)

My invention relates to machines for attaching heels to shoes, it concerning more particularly the means for presenting heel-portions, as a base and top-lift, to a jacked shoe for their attachment.

5 In heelng shoes, it is sometimes desired to use bases and top-lifts which have been prebreasted, or brought to a condition at the breast-surfaces at which only a finishing operation is required after attachment. This is advantageous, because 10 it avoids the danger of cutting the outsole during breastng or of exposing a depression in the sole adjacent to the heel after the breast-cut has been made, the depression being caused by the pressure applied in the heeler to a sole in 15 temper. When thus operating upon prebreasted heels, it is not satisfactory to locate them in their holders in the usual manner by contact of a fixed fork with the rear surface in connection with an opposite yieldable breast-bar. Differences 20 in the amounts previously taken from the breasts will prevent accurate registration of the top-lift and base and will vary the pitch of the attached heel. Consequently, it is desirable to locate the heel-portions by contact with the breast, and, for 25 this purpose, the breast bar is normally fixed upon its swing-plate or carrier, while the rear fork is yieldable.

With such an arrangement as that just described, when there is a change in the character 30 of the heel to be attached, it may be necessary to shift its portions, as the base and top-lift, forwardly or rearwardly upon the carrier. I facilitate this operation, as an object of my invention, by providing means to move one of the heel-contacting 35 members of one of the holders for a heel-portion, as that for the base, and through connections to this, effect the correct movement of a contact member for the other holder, or that for the top-lift. Thus, by a single action on the 40 part of the operator, the elements are simultaneously located in both holders. Since it may be preferable not to impart the same movement to the members, I may furnish means for varying the relative normal positions of the members. In 45 this way, for example, when the attachment of the heel is completed, the base may be caused to project somewhat outside the top-lift. The breast of the base may then be scoured into registration with that of the lift, using the latter as a gage. 50 In the embodiment of the invention herein disclosed, the breast-bars of the base- and lift-holders are movable upon a swing-plate and are connected by a bar having sliding engagement with each. By a projection from the connecting 55 bar-guided in the plate, a movement of one breast-

bar will be communicated to the other in a definite relation. By altering the position of the projection upon the connecting bar, the initial relation between the breast-bars may be varied to give departures from exact registration of the 5 breasts of the base and lift.

When a jacked shoe to which a heel-base has been nailed is brought into engagement with a top-lift in its holder for the spanking operation, the shoe may be turned slightly about the longitudinal axis of the jack, especially if a band-clamp is not employed, so the breasts of the two heel-portions will be out of registration angularly about such axis. It is another object of my invention to correct this condition. For this purpose, the heel-contacting member, as the breast-bar, which is employed to determine the position of the heel-portion, is arranged to swing under the influence of the work so it may thereby restore the disturbed registration. Further, the member 15 may be provided with means to change the position of the work to aid in the correcting action. As herein disclosed, the breast-bar of the top-lift-holder has a supporting or body-portion, a 20 work-contacting portion and an intermediate 25 yieldable portion. This work-contacting portion has a downwardly and inwardly inclined surface which the breast of the attached base upon the jacked shoe will engage when spanking pressure is applied. The forces thus created tend to turn 30 the shoe with its base upon the jack and also to turn the yieldable contacting portion of the breast-bar and thus the top-lift in the holder. In 35 this manner, substantial registration between the heel-portions is assured.

In the accompanying drawing, illustrating one of the several possible forms which my invention may assume,

Fig. 1 is a top plan view of my improved holding 40 means for heel-portions;

Fig. 2, a broken sectional elevation through the top-lift-holder, with a jacked shoe appearing in lift-spanking position;

Fig. 3, a section upon the line III—III of Fig. 1, 45 and

Fig. 4, an elevation of the swing-plate, viewed from the front.

At 10 (Fig. 1) appears a fragment of the frame of a heel-attaching machine, such as is disclosed in Letters Patent of the United States No. 1,157,688, Glidden, October 26, 1915, upon which frame is vertically movable a crosshead 12, the die-block 13 of which has openings to receive nail-drivers 14. Between the die-block and a 50 jack 16 a shoe, as shown at S in Fig. 2, is 55

clamped for the base-nailing and top-lift-spanking operations.

A swing-plate or like carrier 18 is pivoted on the cross-head at 20 and by connections at 22 5 may be oscillated to present above the die-block, in operating position, either a base-holder *b* or a top-lift-holder *t*. The base-holder has a bar 24 which will locate by contact with its inner edge a heel-base, indicated at B in Fig. 1. From this 10 bar projects rearwardly a shank 26 guided in ways 28 on the plate. By a screw 30, mounted at 32 to turn upon the swing-plate and threaded to the shank, the breast-bar may be adjusted in or out to change its relation to the points of insertion of 15 the nails which are carried upon the drivers 14. The breast of the base will be held against the bar 24 by a fork 34, having its shank 36 guided in ways 38 upon the swing-plate and urged against the rear of the base by a spring 40.

20 The top-lift-holder *t* has a rear fork 42, mounted and urged outwardly by a spring 44 in the same manner as that of the base-holder. It is opposed by a breast-bar 46, the shank of which is guided upon the swing-plate, as is that of the 25 associated holder but without adjusting means connected to said shank. This breast-bar for the top-lift is made in three parts: The support or body 46 has secured to it a layer of yieldable material 48, which may be of rubber vulcanized 30 in place. To the free face of this rubber there is attached, also by vulcanization, a work-contacting plate 50, which may be considered as a yieldable breast-bar. By thus connecting the plate 50, it may be swung or displaced angularly, 35 having a limited movement of oscillation about a vertical axis, as that of the jack 16 when this is in operating position. At the inner upper edge of the plate 50 is a downwardly and inwardly inclined surface 52 leading to the work-contacting 40 surface 54. This surface 52 is so located that it will be engaged by the corner of the breast-edge of an attached base as this descends for the lift-spanking operation, unless said edge is already in position to register correctly with the top-lift. 45 When out of registration, this contact will exert a turning force upon the shoe S about the last-pin 56 of the jack, thus tending to correct the location of the breast of the base with respect to that of the top-lift in the holder. At the same 50 time, the contact-plate 50 is subjected to an opposite turning force and, yielding upon its mounting, will tend to bring the lift into registration with the base. This double action shortens the time required to effect registration, this being 55 especially useful because of the rapidity of the spanking movement and the short distance through which it occurs.

To communicate the adjusting movement of the base-breast-bar 24 to the top-lift-breast-bar 60 46, these two bars are formed with longitudinal ways 60 and 62, respectively. In these ways, the angularly disposed arms of a bar 64 are movable. 65 This connecting bar 64 is compelled to move in a predetermined path by a projection from its under side, this being shown as a roll 66 arranged to travel along a slot 68 in the plate 18. The slot preferably lies along a line extending through the swing-plate axis 20 and bisecting the angle between the center lines of the holders *b* and *t*, 70 which pass through the same axis. The roll 66 may be varied in position upon the bar 64 by adjustment along a slot 70, in which it is clamped by a bolt 72. With the roll located at the center of the juncture of the arms of the bar 64, movement 75 of the breast-bar 24 by the adjusting screw

30 will correspondingly carry the breast-bar 46 with its plate 50 in or out, from initial positions at which registration would be effected between the breasts of a base and a lift in the holders. The difference in the direction of travel of the 5 two breast-bars will be compensated for by the capacity for relative movement between said bars and the connecting bar. Any adjustment of the breast-bar for the base will thus be transmitted to that for the lift to give throughout the entire 10 range unfailing registration. If, on the other hand, a projection of one breast-edge beyond the other is desired, then the roll 66 is shifted in its 15 slot so the arms of the bar 64 will change the normal relation of the breast-bars 24 and 46 20 in the proper direction. When the roll is fixed in place, this locates the contact-surfaces of the breast-bars at different distances from the axis of the swing-plate, and one of the breast-surfaces of the attached base and lift will project beyond the other. As long as the roll is retained in its chosen position, this relation between the two breast-bars will be maintained for all adjustments by the screw 30.

In the use of this organization, the operator 25 by the screw 30 positions the breast-bar 24 to give the desired location of the heel-base contacting with it with respect to the nailing mechanism of the heeler. In so doing, he communicates the adjustment through the connecting bar 64 to the 30 top-lift-breast-bar 46 without further attention. Exact breast-registration or a definite amount of overlap will have been determined by adjustment of the roll 66. A heel-base B and a top-lift T being 35 in place in the holders *b* and *t* upon the swing-plate 18 and a shoe S upon the jack 16, during the first half of an operating cycle of the heeling machine, the holder *b* is over the die-block, and the base is nailed in place upon the shoe by the action of the drivers 14. During the second half 40 of the cycle, the connections 22 bring the holder *t* over the die-block. The nailing operation will have left the base upon the jacked shoe with the desired angular relation between its breast and that of the top-lift, and the application of spanking pressure will find the heel-portions correctly located, unless the operator has turned the shoe angularly about the last-pin 56 of the jack. In 45 that case, however, the displaced corner at the breast-edge of the descending base will engage the inclined surface 52 of the contact-plate 50 upon the breast-bar for the top-lift, exerting upon the work a force tending to turn the breast of the heel into registration with the surface 54 of the plate and of the top-lift-breast. Simultaneously, the intermediate portion 48 of the breast-bar yields, so that a further corrective movement of the contact-plate itself in the opposite direction is caused. Thus, the breasts of the 50 base and top-lift are brought to the desired relation. 55

Having described my invention, what I claim as new and desire to secure by Letters Patent of the United States is:

1. In a heel-attaching machine, a movable carrier, two holders for heel-portions mounted thereon, each holder having a work-contacting member variable in position, means arranged to move one of the members, and connections for causing this movement to be communicated to 70 the contact member of the other holder. 65
2. In a heel-attaching machine, a movable carrier, two holders for heel-portions mounted thereon, each holder having a work-contacting member variable in position, means arranged to 75

move one of the members, and connections for causing this movement to be communicated to the contact member of the other holder, said connections including means for varying the 5 relative normal positions of the members.

3. In a heel-attaching machine, a movable carrier, two holders for heel-portions mounted thereon, each holder having a work-contacting member variable in position, means arranged to 10 move one of the members, and connections for causing this movement to be communicated to the contact member of the other holder, said connections moving with the holders and being guided in such movement in a predetermined 15 path.

4. In a heel-attaching machine, a movable carrier, two holders for heel-portions mounted thereon, each holder having a work-contacting member variable in position, means arranged to 20 move one of the members, and connections for causing this movement to be communicated to the contact member of the other holder, said connections moving with the holders and being guided in such movement in a predetermined 25 path and including means for varying the relative normal positions of the members.

5. In a heel-attaching machine, a swing-plate, a heel-base-holder and a top-lift-holder mounted thereon and each having a movable work-contacting member, and a connecting member having sliding engagement with each contact member.

6. In a heel-attaching machine, a swing-plate, a heel-base-holder and a top-lift-holder mounted thereon and each having a movable work-contacting member, and a connecting member having sliding engagement with each contact member and being bodily movable in a path determined by engagement with the swing-plate.

7. In a heel-attaching machine, a swing-plate, 40 a heel-base-holder, and a top-lift-holder mounted thereon and each having a movable work-contacting member, and a connecting member having sliding engagement with each contact member and provided with means arranged to vary 45 the normal relation of the contact members to each other.

8. In a heel-attaching machine, a swing-plate, a heel-base-holder and a top-lift-holder mounted thereon and each having a yieldable rear fork and 50 an adjustable breast-bar in each of which bars are ways, and a connecting bar extending into the ways.

9. In a heel-attaching machine, a swing-plate, a heel-base-holder and a top-lift-holder mounted thereon and each having a yieldable rear fork and an adjustable breast-bar in each of which bars are ways, and a connecting bar extending 55 into the ways, said connecting bar being provided with a projection guided by the swing-plate.

10. In a heel-attaching machine, a swing-plate, a heel-base-holder and a top-lift-holder mounted thereon and each having a yieldable rear fork and an adjustable breast-bar in each of which bars are ways, a connecting bar extending 60 into the ways, said connecting bar being provided with a projection guided by the swing-plate, and means arranged to fix the projection at different points upon the connecting bar.

11. In a heel-attaching machine, a swing-plate 70 provided with a slot, a heel-base-holder and a top-lift-holder mounted thereon and each having a yieldable rear fork and an adjustable breast-bar, in each of which bars are ways, and a connecting bar extending into the ways and having a roll entering the plate-slot.

12. In a heel-attaching machine, a swing-plate provided with a slot, a heel-base-holder and a top-lift-holder mounted thereon and each having a yieldable rear fork and an adjustable breast-bar, in each of which bars are ways, a 5 connecting bar extending into the ways and provided with a slot, and a roll variable in position in the bar-slot and extending into the plate-slot.

13. In a heel-attaching machine, a movable carrier, and a holder for a heel-portion mounted 10 upon the carrier and having opposite members for contact with the heel-portion, one of the members being arranged to swing under the influence of the work and being provided with means for contact with the work to change the 15 position of said work.

14. In a heel-attaching machine, a movable carrier, and a holder for a heel-portion mounted 20 upon the carrier and having opposite members for contact with the heel-portion, one of the members being movable toward and from the other and said other member being arranged to swing in the direction of such movement.

15. In a heel-attaching machine, a movable carrier, and a holder for a heel-portion mounted 25 upon the carrier and having opposite members relatively movable to contact with the heel-portion and clamp it between them, one of the members having a yieldable portion for contact with the heel-portion.

16. In a heel-attaching machine, a movable carrier, and a holder for a heel-portion mounted upon the carrier and having opposite members for contact with the heel-portion, one of the members having a yieldable portion for contact with 35 the heel-portion, said yieldable portion being provided with a surface inclined outwardly from the opposite member to receive contact of the work.

17. In a heel-attaching machine, a swing-plate, and a holder for a heel-portion mounted thereon 40 and including a rear fork and a breast-bar, said breast-bar being provided with a supporting portion, a work-contacting portion and an intermediate yieldable portion.

18. In a heel-attaching machine, a swing-plate, 45 and a holder for a heel-portion mounted thereon and including a rear fork and a breast-bar, said breast-bar being provided with a supporting portion, a work-contacting portion and an intermediate yieldable portion, the work-contacting 50 portion having a downwardly and inwardly inclined surface adjacent to the work-contacting surface.

19. In a heel-attaching machine, a top-lift-holder comprising a breast-bar having a layer of 55 yieldable material attached to the breast-bar and a lift-contacting plate secured to the yieldable layer.

20. In a heel-attaching machine, a top-lift-holder comprising a breast-bar having a layer of 60 yieldable material attached to the breast-bar and a lift-contacting plate secured to the yieldable layer, the plate being provided with an inclined edge for engagement with a heel-base to which the top-lift is to be applied.

21. In a heel-attaching machine, a jack upon 65 which a shoe having an attached heel-base may turn about the axis of the jack, and a top-lift-holder including a breast-bar yieldable about the axis of the jack.

22. In a heel-attaching machine, a jack upon 70 which a shoe having an attached heel-base may turn about the axis of the jack, and a top-lift-holder including a breast-bar yieldable about the axis of the jack and provided with an inclined 75

surface with which the heel-base upon the jacked shoe may contact.

23. In a heel-attaching machine, a jack for a shoe having an attached heel-base, and a top-lift-holder co-operating with the jack and including a breast-bar yieldable about the axis of said jack.

24. In a heel-attaching machine, a jack for a

shoe having an attached heel-base, and a top-lift-holder cooperating with the jack and including a breast-bar yieldable about the axis of said jack and provided with an inclined surface with which the breast-edge of the heel-base may contact to produce registration between the top-lift and base. 5

JOHN W. ASHLEY.
